(57) **CLAIM**

The ornamental design for a combined dental light and suction cups for attachment to mirror, as shown and described.

DESCRIPTION

FIG. 1 is a perspective view of a combined dental light with suction cups for attachment to mirror showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a left side elevational view thereof; and,

FIG. 7 is a right side elevational view.

My dental light with suction cups for attachment to mirror is characterized by two white LED lights with a switch in the front and three suction cups on the rear.
